UNITED STATES PATENT OFFICE.

CHARLES W. MOWRY, OF LYNN, MASSACHUSETTS, ASSIGNOR TO THE PEOPLE OF THE UNITED STATES AND TERRITORIES.

WALL SPRINKLER-HEAD.

1,288,122.

Specification of Letters Patent. Patented Dec. 17, 1918.

Application filed February 18, 1918. Serial No. 217,841.

To all whom it may concern:

Be it known that I, CHARLES W. MOWRY, a citizen of the United States, residing at Lynn, county of Essex, State of Massachusetts, have invented an Improvement in Wall Sprinkler-Heads, of which the following description, in connection with the accompanying drawing, is a specification, like characters on the drawing representing like parts.

This invention relates to improvements in sprinkler heads. These heads are operatively connected with a water supply under pressure. When a fire occurs or it is desired to operate the heads a valve in the water supply system is opened and the water flows therefrom out through the heads.

The object of this invention is to produce an improved sprinkler head.

This invention is particularly directed to the provision of a wall sprinkler head adapted for use to protect windows, side walls and similar parts of structures in which a sheet or curtain of water is advantageous.

The invention also has for its object the protection both of a wall surface whether provided with windows or not and a cornice so that all of the surfaces may be thoroughly wetted and with an economical use of the water.

Other objects of the invention will more fully appear from the following description and the accompanying drawings and will be particularly pointed out in the annexed claims.

In the accompanying drawings, there has been disclosed a structure designed to carry out the objects of the invention, but it is to be understood that the invention is not confined to the exact features shown, as various changes may be made within the scope of the claims which follow.

Figure 1 is a view in elevation of a wall showing the invention in various ways;

Fig. 2 is an enlarged sectional view of a wall showing a cornice and window with the device applied;

Fig. 3 is a front elevation of the improved sprinkler head;

Fig. 4 is a plan view of the same;

Fig. 5 is a sectional view on the line 5—5 of Fig. 3;

Fig. 6 is a sectional view on the line 6—6 of Fig. 3;

Fig. 7 is a diagrammatic view illustrating how the water is distributed.

The selected embodiment of the novel sprinkler head here shown is one particularly adapted to deflect the water forced from the sprinkler head outlet in a fan-like sheet. This type of head and deflector is advantageous in providing a uniform sheet of water flowing down the side of a building or windows. The novel structure of this head affords a water outlet and a deflecting surface acting to cause water discharged through the outlet to pass off the surface in a fan-like sheet with the discharge so concentrated in the central portion of the sheet that the sheet of water flowing down a surface located at a predetermined distance from the outlet shall be of substantially uniform volume and in which the outlet is sufficiently large to insure a relatively slow velocity of the sheet of water flowing down said surface.

The orifice is made relatively large depending upon the pressure or head of the water so that even with the lowest pressures which occur in practice a sufficient volume of water may flow therethrough at a relatively slow velocity to provide for wetting the required area of wall surface. This is particularly desirable at the top of tall buildings where the pressures are frequently very low.

While this improved head may be formed of a plurality of complementary parts, it is preferable to form the head in one integral casting. The nipple 1 is externally threaded to be received in engagement with a suitable fitting on a supply pipe 2. Direct communication with the pipe interior is thereby afforded and water under pressure in the pipe may be forced out through the sprinkler head outlet 3. It is with the deflection and distribution of this released water that this invention is concerned.

The outlet 3 of this improved head is made larger than those of other existing heads and thus choking or clogging is practically eliminated and a larger volume of water may be delivered in a given time and at a lower velocity. The nipple 1 is provided with a base such as the square base 4. Cast integrally with this base are the parts which broadly comprise the water deflecting and controlling surfaces. The deflecting surface 5 may be described as substantially like a

segment of a concaved cone. The apex 6 of this conodial segment is preferably not positioned immediately under the outlet 3 but is adjacent one side of the water outlet so that 5 the water forced from the outlet will be effectively deflected by the surface 5 of the conodial segment.

In order to attain the desired deflection of the water in a uniform sheet this segmentally conodial surface 5 is provided with an elongated pocket or depression 7. This depression longitudinally extends, as shown, substantially in a medial line of the surface from a point adjacent the apex 6 to the base 15 of the surface 5. The width and depth of the elongated depression lessens as it approaches the apex portion which portion is substantially flattened and the depression gradually merges into the flattened apex 6. 20 The greatest width and depth of the depression 7 is substantially opposite the longitudinal axis of the outlet. The major function of this medial depression is to aid in effecting a concentration of the water in 25 the central portion of the sheet formed by the whole deflecting surface of the head.

The base of the conodial surface 5 terminates in a flange 8 which is preferably integrally formed and projects, in this selected embodiment, at substantially a right angle to the axis of the surface 5. This angle may of course be varied within permissive limits but a flange made at the angle indicated functions advantageously with the 35 segmentally conodial surface here shown.

Means are also provided on this novel sprinkler head to direct water forced from the outlet and to govern the angle of distribution. A retaining wing 9 is formed on 40 each side of the surface 5 extending from the apex to the base. Herein, these wings 9 are shown as integral webs extending from a corner of the square base 4 to the base flange 8. In this particular head, these retaining 45 wings 9 form an obtuse angle with each other. Water, tending to be forced off the sides of the conodial deflecting surface, is directed to the surface 5 by the opposed wings so that they retain the water and substantially govern the width of the angle of 50 distribution of the fan-like sheet of water resultant from this sprinkler head structure.

Sprinkler heads of this general type are 55 usually employed in series and a particular adaptation of these novel heads is indicated in Figs. 1 and 2, wherein a sprinkler system pipe 2 is supported along the wall of a building near the top. The section of wall shown 60 is that of a building several stories high and having variant sized windows and a blank wall portion. A sprinkler head of this improved type is positioned opposite each window such as the ordinary windows 10 or in 65 pairs adjacent larger windows 11. Each

sprinkler head of this novel form is capable of jetting a sheet of water of substantial thickness against the uppermost window of the vertical tier opposite the sprinkler head. In the case of the blank wall 12, the sprinklers are positioned a distance apart such that a substantially uniform, continuous sheet of water forming what is known as a water-curtain flows down the wall.

By the employment of this improved 75 sprinkler head, a greater volume of water may be forced from the outlet at a relatively slower velocity than is common in other heads. The result herein is that the larger volume is discharged from the deflecting surface of this head at a relatively slow velocity. The fan-like sheet impacts with the window, wall or other surface at a relatively slow velocity, the spattering rebound of the sharp forceful impact is obviated and 80 a continuous sheet of water is formed to flow down the surface. Further, the above-noted concentration of water in the central portion of the surface 5 (broadly, the central one-third) causes the fan-like sheet discharged from the flange 8 to be of greater thickness or volume in the corresponding portion. This prevents the usual thinning out in the center of an impacted stream of water so that the sheet of water, resultant 85 from this novel head and flowing down the impact surface, is of substantially uniform volume.

The invention comprises the use in connection with sprinkler heads for wetting the 100 wall surface of a series of sprinkler heads adapted for wetting a cornice so that the entire surface area of the building may be protected against fire.

In the construction illustrated in Fig. 1 105 the supply pipe 2 is provided with a series of cornice sprinklers 13. In the adaptation illustrated and for convenience in piping these cornice sprinkler heads are shown as located opposite the wall sprinkler heads and connected to the same fittings but it is obvious that this particular arrangement is not essential and that the two sets of sprinklers need not necessarily be connected to the same pipe.

The sprinkler heads 13 are designed to project or jet the water issuing therefrom upwardly against the under surface of the cornice and are so constructed as thoroughly to wet the cornice. For this purpose they 110 may preferably be of the construction illustrated in another application Serial No. 217,842 filed coincidently herewith by this inventor. As so constructed these cornice 115 sprinklers project divergent sheets of water which are relatively long and narrow and at the same time a small amount of water directly up between the divergent sheets so that the entire surface is wetted with the minimum amount of water.

There is thus provided in the combination of the two sets of sprinkler heads a means for thoroughly wetting the wall surface and the projecting cornice of a building 5 in a simple, efficient and economical manner.

Having fully described my invention what I claim as new and desire to secure by Letters Patent is:

1. A sprinkler head for wall surfaces comprising a water outlet, a deflecting segmental concaved conoidal surface with its apex adjacent said outlet and its base terminating in a flange, a longitudinal medial depression in said deflecting surface, and retaining wings at the sides of said surface, the said surface with its depression and the said flange and wings being so shaped, proportioned and related as to cause water discharged through the outlet at a given volume and velocity to pass off the flange in a fan-shaped sheet with the discharge so concentrated in the central portion of the sheet that the sheet of water flowing down a surface located at a predetermined distance 20 from the outlet shall be of substantially uniform volume.
2. A sprinkler head such as set forth in claim 1, in which the said flange extends at substantially a right angle to the axis of said surface.
3. A sprinkler head such as set forth in claim 1, in which the apex of said surface is adjacent and at one side of the water outlet.
- 35 4. A sprinkler head as set forth in claim

1, in which the apex of said surface is adjacent and at one side of the water outlet and in which said flange extends at substantially a right angle to the axis of said surface.

5. A sprinkler head such as set forth in claim 1, in which the said outlet is of sufficiently large area to secure a relatively slow velocity of the sheet of water at its impact with the said surface whereby any substantial amount of spattering or rebound is prevented.

6. In a sprinkler head for wall surfaces, a water outlet having its area sufficiently large to produce a relatively low velocity of 50 flow at a predetermined distance from the outlet, and a deflecting surface having a configuration acting to cause water discharged through the outlet at a given volume and velocity to pass off the surface in a fan-shaped sheet with a discharge so concentrated in the central portion of the sheet as to produce a sheet of uniform volume along a straight line at said predetermined distance from the outlet, whereby the impact of 55 the sheet with a surface located at said predetermined distance from the outlet shall take place at a relatively slow velocity and whereby the sheet of water flowing down the impacted surface shall be of substantially uniform volume.

In testimony whereof, I have signed my name to this specification.

CHARLES W. MOWRY.
